UNITED STATES PATENT OFFICE.

JOHN CLARENCE SPARKS, OF GEORGETOWN, SOUTH CAROLINA.

WRENCH.

No. 918,787.

Specification of Letters Patent.

Patented April 20, 1909.

Application filed December 18, 1908. Serial No. 468,201.

To all whom it may concern:

Be it known that I, JOHN CLARENCE SPARKS, a citizen of the United States, residing at Georgetown, in the county of Georgetown and State of South Carolina, have invented a new and useful Wrench, of which the following is a specification.

This invention relates to wrenches and has for its object to provide a simple, strong, and compact wrench provided with a plurality of independent jaw plates, each having thereon a pair of jaws differing in spread or shape from the other jaws.

Another object is to provide a handle to which any of the jaws may be removably secured, and to further provide a locking member disposed within said handle and adapted to be operated to engage one of a plurality of recesses formed in the jaw plate, whereby the latter may be adjusted and yieldingly held in adjusted position at any angle.

Another object is to provide a positive keeper which may be operated to permanently hold the locking member in engagement with a recess in the jaw plate.

With these and other objects in view, as will more fully hereinafter appear, the present invention consists in certain novel details of construction and arrangement of parts, hereinafter fully described, illustrated in the accompanying drawings, and more particularly pointed out in the appended claims, it being understood that various changes in the form, proportion, size and minor details of the device may be made without departing from the spirit or sacrificing any of the advantages of the invention.

In the accompanying drawings forming a part of this specification.—Figure 1 is a front elevation of the invention. Fig. 2 is a longitudinal sectional view of the same. Fig. 3 is a detail section of the keeper. Fig. 4 is a front elevation of a modified form of jaw plate.

Similar numerals of reference are employed to designate corresponding parts throughout.

In carrying out the invention I provide a suitable handle to one end of which is pivoted a suitable jaw plate. The latter may be turned on its pivot so as to occupy a position on either side of the handle. The latter is interiorly provided with a reciprocating plunger, the nose of which enters a recess formed in that end of the handle adjacent the jaw plate, and is adapted when

moved to enter one of a series of recesses formed in the jaw plate, whereby the latter is rigidly held in whatever position it may occupy on either side of the handle. A suitable operating lever is provided for the plunger and is pivoted to the handle in such manner that when the latter is pressed in the natural way for tightening a nut, the lever will also be depressed and by means of a connection between the latter and the plunger, the plunger will be forced into engagement with the recess of the jaw plate.

The handle consists of four parts, namely, a rib 1 which may be of any suitable length, preferably of metal, and having a laterally curved portion 2 at one end. That portion of the rib extending from the laterally curved end 2 is slightly inclined or flexed. The rib forms a support for a pair of handle plates 3 and 4. Each of these members is considerably greater in length than the rib and are suitably secured on opposite sides of the latter. The lower end of each plate is rounded to the shape of the curved portion 2 of the rib, and each handle is so positioned on the rib that one of its longitudinal sides and rounded end is coincident with the outer face of the rib. The opposite or free ends of the plates project beyond the end of the rib, and secured between the plates is a bridge 5, formed integrally with the rib 1. The length of the bridge is substantially the same as the width of the plates, and the ends are shaped to conform to the outline of the handle. The forward side of the bridge or that remote from the curved end of the rib 2 is concaved, as shown at 6, and in the center of this concaved face is formed an inwardly extending opening communicating with the space between the side plates 3 and 4.

A jaw plate in the present instance, is shown to be formed of a flat piece of metal sufficiently thick for the work to be performed by it. The body portion 7 of the jaw plate has a semi-circular outline indented throughout with notches or recesses 8. The jaws 9 project outwardly from the body portion 7 and are spaced to fit the work on which the wrench is to be used, the intention being to have a plurality of jaw plates for each handle. The body portion 7 of the jaw plate is designed to enter the space between the free end portions of the handle plates 3 and 4, and a central opening 10 is formed in the jaw plate which is adapted to be brought into coincidence with a similar opening in

each of the handle plates 3 and 4. Thus when the openings are in alinement, a suitable pivot bolt 11 is inserted to hold the parts together. From the foregoing it will be seen that I have provided a handle having a freely movable jaw plate, the jaws of which may be turned to operative position on either side of the handle.

In order to secure the jaw plate in its adjusted positions, the following mechanism is employed:—By referring now to Fig. 2, it will be seen that between the body portion of the handle plates 3 and 4 is a plunger rod 12, one end of which extends through the opening formed in the center of the bridge 5, and the opposite end of which is provided with a head 13, the face of which has a slightly depressed cam surface. An operating lever 14, preferably of a single piece of metal, has one end pivoted between the handle plates 3 and 4 adjacent the bridge 5. The operating lever is formed to the shape of the rib 1, and at its free end is curved laterally similar to the curved portion 2 of the rib, and in the end of this curved portion a suitable detent 15 is formed, into which projects the terminal of the curved portion 2 of the rib. Thus it will be seen that when the operating lever is secured in place, as shown in Fig. 2, its free end will be held from moving out of the space between the side plates 3 and 4, by means of the walls of the detent abutting against the terminal of the curved portion 2 of the rib. The detent is so formed that the operating lever is permitted to project beyond one side of the handle plates 3 and 4 for a distance equal to one-half its width, or substantially so, so that when the handle is grasped by the operator in the act of tightening the nut, the pressure on the handle will force the outer side of the operating lever inward to a position substantially coincident with the sides of the handle plates. Operative connection between the operating lever and plunger head 13 is formed by means of a cam stud 16. This member is substantially egg-shaped in outline and has its narrow end pivoted between the handle plates 3 and 4 adjacent the curved face of the rib 2. The stud is so positioned that the opposite sides of its widened end will bear on the cam surface of the head 13, and the laterally curved end portion of the operating lever 14. Thus it can be seen that when the latter is depressed, the stud, while bearing against the cam surface of the head 13, will force the end of the plunger rod out of the opening in the bridge 5 and into the space between the free end portions of the handle plates and into one of the recesses 8 of the jaw plate.

In order that the parts may be returned to their original positions, or in other words, that the free end of the plunger may leave the recess in the jaw plate when the pressure on the lever bar 14 is removed, a suitable

coiled spring 17 is employed. This member surrounds the body portion of the plunger rod 12 and has its terminals bearing on the inner face of the bridge 5 and plunger head 13. Thus it will be seen, that when desired, the wrench may be operated similar to a ratchet and the final tightening turns given to a nut without removing the jaws therefrom.

In order that the operating lever may be kept depressed and the end of the plunger held within one of the recesses 8 of the jaw plate at all times, the following device is employed:—By referring now to Fig. 2 it will be seen that adjacent the pivoted end of the operating lever, the latter is reduced somewhat in width, or in other words, an oblong recess is formed in its inner side. On that end of the recess remote from the pivotal point of the lever a longitudinally disposed seat 18 is formed, and in one of the handle plates a longitudinal slot 19 is formed, which is adapted to register with the seat 18 when the lever is pressed to the limit of its inward movement. The length of the slot 19 is somewhat greater than the length of the seat 18, and that end of the former adjacent the pivotal point of the lever 14 lies considerably in advance of that end of the recess in which the seat 18 is formed. A keeper in the present instance is shown to consist of a bolt 20 loosely fitted within the slot 19, and having on its outer end a bowed spring 21, which bears on the outer surface of the handle plate in which the slot 19 is formed. The shank of the bolt 20 is provided with a shoulder 22 which bears on the inner face of the handle plate and prevents the bolt from falling out. Thus it will be seen that when the lever 14 is depressed and the bolt 20 moved into the seat 18, the lever will be prevented from returning to its normal position when pressure is removed. The bowed spring 21 serves the double purpose of preventing the bolt 20 from falling inward and holding the bolt at that end of the slot remote from the seat 18.

The modified form of jaw plate shown in Fig. 4 is similar to that already described, with the exception that it is provided with a pair of angularly disposed jaws 23 and 24, one of which has a roughened surface, as shown at 25.

From the foregoing, the operation of the device will be readily understood, and it will be seen that I have provided a wrench which is simple in structure and adjustable to most any desired angle.

What is claimed is:—

1. In a wrench the combination with the handle of a recessed jaw plate pivoted to one end thereof, a plunger and an operating lever combined with the handle, the said lever being provided with a seat, a connection between the lever and the plunger whereby when the lever is pressed the plunger will be

forced into engagement with the recessed jaw plate, and a keeper slidably mounted in the handle and being arranged to register in the seat, whereby the plunger will be held in engagement with the recessed jaw plate.

2. In a wrench the combination with a handle of a recessed jaw plate pivoted to one end thereof, a plunger to engage said jaw plate, an operating lever for actuating the plunger, the said lever being provided with a seat, and a keeper slidably mounted in the

handle and being arranged to register in the seat, whereby the plunger will be held in engagement with the recessed jaw plate.

In testimony that I claim the foregoing as 15 my own, I have hereto affixed my signature in the presence of two witnesses.

JOHN CLARENCE SPARKS.
